(57) **CLAIM**

The ornamental design for a door holder as shown and described.

DESCRIPTION

FIG. 1 is a top perspective view of a door holder in accordance with my new design;

FIG. 2 is a bottom perspective view from a first angle of the door holder as shown in FIG. 1;

FIG. 3 is a bottom perspective view from a second angle of the door holder as shown in FIG. 1;

FIG. 4 is a front view of the door holder as shown in FIG. 1;

FIG. 5 is a rear view of the door holder as shown in FIG. 1;

FIG. 6 is a first side view of the door holder shown in FIG. 1;

FIG. 7 is a second side view of the door holder shown in FIG. 1;

FIG. 8 is a top view of the door holder shown in FIG. 1;

FIG. 9 is a bottom view of the door holder shown in FIG. 1;

FIG. 10 is a perspective view of an embodiment of a door holder in accordance with my new design;

FIG. 11 is a bottom perspective view from a first angle of the door holder as shown in FIG. 10;

FIG. 12 is a bottom perspective view from a second angle of the door holder as shown in FIG. 10;

FIG. 13 is a front view of the door holder as shown in FIG. 10;

FIG. 14 is a rear view of the door holder as shown in FIG. 10;

FIG. 15 is a first side view of the door holder shown in FIG. 10;

FIG. 16 is a second side view of the door holder shown in FIG. 10;

FIG. 17 is a top view of the door holder shown in FIG. 10; and,

FIG. 18 is a bottom view of the door holder shown in FIG. 10.

The broken lines depict portions of the door holder that form no part of the claimed design.

1 Claim, 14 Drawing Sheets
